UNITED STATES PATENT OFFICE.

JOSEPH HROMAS, OF ANSLEY, NEBRASKA.

AUTOMOBILE RADIATOR ATTACHMENT.

Application filed May 1, 1925. Serial No. 27,334.

This invention relates to a novel attachment for an automobile radiator, which is intended to be associated with the radiator cylinder to facilitate filling of the radiator 5 with water.

Water buckets and other wide mouth receptacles are frequently employed for pouring water into automobile radiators, and in 10 windy weather, the stream of water flowing from the bucket is blown to such an angle as to make it indeed difficult to pour it through the restricted filler neck.

In view of the foregoing circumstances, I have evolved and produced a novel attachment 15 which is to be associated with the radiator neck, and which includes a water pan for collecting and directing the water into the radiator, whereby to facilitate filling in windy weather.

It is a feature of the invention to enclose 20 the water pan in a casing which is preferably of ornamental design, so that the device may function additionally as a radiator ornament.

It is a further feature to provide the 25 casing with a hinged cover, which, when swung up, may act as a shield, to prevent blowing of water out of the pan, this cover also constituting the means for closing the 30 filler neck.

Other features and advantages of the invention will become apparent from the following description and drawings:

In the accompanying drawings, forming 35 a part of this application, and in which like numerals are employed to designate like parts throughout the same:

Figure 1 is a front elevation of the upper 40 portion of a radiator, showing the improved attachment in position thereon.

Figure 2 is a top plan view of Figure 1, with a portion of the cover plate broken away.

Figure 3 is a section, taken approximately 45 upon the plane of the line 3—3 of Figure 2.

Figure 4 is a detail fragmentary section showing the retaining means for the hinged 50 cover.

As before intimated, the primary feature of the improved attachment is the water pan 55 1, which in the present instance is preferably of elongated rectangular form, the same being provided at its center with an opening through which the radiator neck 2 projects.

It will be observed that appropriate packing 60 surrounds the neck, to provide a fluid tight joint. It will also be observed that

the bottom of the pan is inclined toward the open end of the neck to facilitate flow of water into the latter. The pan 1 is housed in a casing 4, the casing being shaped to conform at its top to the pan and tapering downwardly and resting upon the automobile radiator 5. In the present instance, the radiator is arched, at its top, and the lower portion of the casing 4 is shaped to conform to the contour thereof. The casing is formed at its end with a pair of attaching ears 6, fastened to the radiator by fastenings 7. As shown in front elevation, the front wall of the casing will be utilized to display an appropriate slogan such as "Safety first". It will be observed from Figure 3, that the top of the casing terminates on a plane with the free edge of the rim of the pan, and that a flanged cover 8 serves to cover the pan. 70 The cover is hinged, as at 9, to permit it to be swung open, to uncover the pan. Also, while it is not essential, the central portion of the cover is depressed, as at 11, and provided with apertures 12, to permit passage of air and heat. Also, a latch 13 is pivoted upon the cover, and is provided with a downturned free end portion carrying a handle 14, the downturned portion having a notch 85 provided in one edge affording a keeper, for a headed stud 15 on the rear wall of the casing. This structure is shown very clearly in Figure 4.

When it is desired to fill the radiator, the hinged cover is swung open to expose the 90 pan and the water is then poured into the pan and overflows into the radiator through the filler neck. By pouring the water comparatively slowly, the radiator can be filled in an efficient manner, without allowing the 95 water to spill and run all over the radiator. Also a wide mouthed receptacle, such as a water bucket may be employed in the filling operation, and no particular skill, in making the stream from the bucket sufficiently 100 small to enter the restricted radiator neck, is necessary. It is only necessary to pour the water into the pan. The hinges of the cover may be such as to frictionally hold the cover in the vertical open position, and the cover 105 may thus serve as a windshield during the filling operation. The presence of the depression in the cover will prevent accumulation of rain water.

These and other advantages and features 110 of the invention have doubtless been made apparent by the foregoing description and

drawings. Therefore, a more lengthy description is deemed unnecessary.

While the preferred embodiment of the invention has been shown and described, it is to be understood that minor changes in the field of invention claimed may be resorted to, if desired.

I claim:

As a new article of manufacture, a combination radiator ornament and water filling device comprising an elongated substantially rectangular water receiving pan provided in its bottom with a central opening for reception of the upper end of a radiator neck, 15 a substantially pyramidal casing surround-

ing said pan and conforming in shape thereto for concealing the latter, the vertex portion of the casing being truncated, the lower end of the side walls of the casing being shaped to conform to the shell of a radiator and being provided with attaching means, the upper edge of said casing terminating on a plane with the edge of the rim of said pan, a cover hingedly connected to said casing and adapted to overlie the truncated portion of the casing and said pan, said cover being substantially flat and formed with a central depression. 20

In testimony whereof I affix my signature. 25

JOSEPH HIROMAS.
